Specification for Design.

Patented Dec. 8, 1914.

Application filed February 16, 1914. Serial No. 819,122. Term of patent 14 years.

To all whom it may concern:

Be it known that I, WALLACE C. SABINE, a citizen of the United States, residing at Boston, in the county of Suffolk and State of Massachusetts, have invented a new, original, and ornamental Design for Pour-Outs for Bottles, of which the following is a specification, reference being had to the accompanying drawing, forming part thereof.

The figure is a side elevation of a pour-out for bottles showing my new design.

I claim:

The ornamental design for a pour-out for bottles as shown.

WALLACE C. SABINE.
